CARD PRINTING MACHINE

Edd C. Oliver, Adrian, Mich.

Application June 15, 1934, Serial No. 730,790

9 Claims. (Cl. 101—269)

This invention relates to card printing machines and the object of the invention is to provide a machine for printing cards in which the pressure applied in the printing operation may 5 be varied by means of a leverage controlled manually by the operator.

Another object of the invention is to provide a card printing machine including a printing bed and a card holding means at one end of the 10 printing bed, the said card holding means being releasable by the operator when the carriage is moved to position over the card holding means.

A further object of the invention is to provide a card printing machine comprising a printing 15 bed having a card holding means at one end and a carriage movable longitudinally of the printing bed, said carriage carrying a pressure roller and a member adapted to be turned in one direction to move the pressure roller into engagement with the card and adapted to be turned in the opposite 20 direction when over the card holder to release the card holding means.

Another object of the invention is to provide an eccentrically mounted pressure roller including 25 a pivoted supporting member having a handle whereby the pressure on the pressure roller may be varied by varying the angular position of the handle in moving the carriage longitudinally of the printing bed.

A further object of the invention is to provide 30 a spring actuated card holder comprising a pivoted card holding member having an edge arranged to engage and grip the card and the pivoted card holding member being turnable on its pivot against the tension of the springs to allow 35 release of the card.

These objects and the several novel features of 40 the invention are hereinafter more fully described and claimed and the preferred form of construction by which these objects are attained is shown in the accompanying drawings in which—

Fig. 1 is a plan view of a card printing machine embodying my invention.

Fig. 2 is a side elevation thereof.

Fig. 3 is a section taken on line 3—3 of Fig. 2.

Fig. 4 is an enlarged section taken on line 4—4 of Fig. 1.

Fig. 5 is an enlarged section taken on line 5—5 of Fig. 1.

Fig. 6 is a reduced section taken on line 6—6 of Fig. 5.

The device, as shown more particularly in Fig. 3, comprises a printing bed 1 which is supported 55 on two channel side members 2 which are se-

cured to the printing bed 1. A track 3 is secured to the opposite longitudinal edges of the printing bed. A carriage bracket 4 is provided at each side of the printing bed 1 and these carriage brackets 4 each carry a series of four rollers 5, 6, 7, and 8, as shown more particularly in Fig. 4. The rollers 5 and 8 are each flanged rollers, as shown in Figs. 3 and 4, and the flanges ride against the outer edges of the printing bed 1 and the track members 3. By this arrangement the 10 carriage brackets 4 may be moved longitudinally of the printing bed in either direction. An elongated U-shaped member 9 is provided, as shown in Figs. 1, 3, 4, and 5, and each end of this U-shaped member is provided with a pivot stud 10 15 which is rotatably mounted in the corresponding carriage bracket 4.

A shaft 11 is mounted in the ends of the U-shaped bracket 9 eccentric to the axis of the pivot studs 10 and a roller 12 is rotatably mounted 20 on the ball bearings 13 supported on the shaft 11.

A handle 14 is also secured to the center of the U-shaped member 9 whereby the member 9 may be turned on the studs 10 which act as a pivot for the member 9. By this arrangement, as 25 will be understood from Fig. 4, the roller 12 may be turned from the position shown in full lines in Fig. 4 to that shown in dotted lines in the said figure. The type 15 are mounted on the printing bed 1, as shown in Fig. 5, or in any other 30 suitable manner and a transverse member 16 is secured to the printing bed 1 by the screws 17. This member 16 is provided with lugs 18, as shown in Figs. 5 and 6, and a plate 19 is provided having depending lugs 20 extending between the lugs 18 and a pin 21 extends through 35 the lugs 18 and 20 so that the plate 19 is pivotally mounted on the two pins 21, shown in Figs. 5 and 6. This plate 19 is provided with a downwardly bent flange 22 at the forward edge and 40 at the rear edge a coiled spring 23 forces the member 19 upwardly on its pivot 21 to force the clamp jaw edge 22 downwardly toward the top surface of the member 16. A guide 24 is secured to the plate 19 and forms a guide for the coiled 45 spring 23. A cross member 25 is provided for the carriage, as shown in Figs. 1, 4, and 5, which extends between the two movable side carriage brackets 4 and is secured thereto by the screws 26 which extend through the adjacent member 50 4 and are threaded into the ends 27 of the cross member 25. By this arrangement, the member 25 rides with the movable carriage and a pair of pins 28 are supported in the cross member 25 on the springs 29.

Threaded through the ends 27 of the member 25 are a pair of adjusting screws 30 which are engaged by the faces 31 of the U-bracket 9 when in the position shown in full lines in Fig. 4. 5 These screws 30 are adjustable and act as stops to limit turning movement of the member 9 on the pivot studs 10 by means of the handle 14. The screws 30 may be so adjusted that the maximum amount of pressure with which the roller 10 12 presses downwardly on the type is accurately limited.

In operation, the carriage is moved to the position shown in Fig. 4 in which position the upturned end 32 of the track 3 provides a stop. At 15 this time, the handle 14 may be turned from the position shown in full lines in Fig. 4 to that shown in dotted lines. When so turned, the pivoted member 9 engages the upper ends of the two pins 28 and forces these pins downwardly against the 20 tension of the springs 29. In this position shown in Fig. 4, the pins 28 are directly over the rear portion of the clamp member 19 and thus force the clamp member downwardly against the tension of the springs 23. This raises the forward 25 edge 22 of the clamp away from the member 16 allowing a card 33 to be positioned on the type 15 so that the edge of the card may be inserted between the clamp edge 22 and the transverse member 16. At this time, the handle 14 may be turned 30 from the position shown in dotted lines in Fig. 4 to that shown in full lines. In this movement, the pins 28 are released to upward movement by the springs 29 and the clamp member 19 is released to turning movement on its pivot 21 by 35 the springs 23. This causes the edge 22 of the clamp member 19 to grip the edge of the card between said clamp edge and the member 16.

As the handle 14 is turned over to the position 40 shown in full lines in Fig. 4, the roller 12 is brought into contact with the upper surface of the card 33, at which time, the carriage is ready for movement longitudinally of the machine. The handle 14 is then in the position shown in Figs. 1, 2, and 3 and the handle may be grasped 45 in order to draw the carriage longitudinally of the machine. In this connection it will be noted that the more pressure exerted in pulling down on the handle the more pressure is applied to the card 33 being printed and the amount of pressure 50 that can be so applied may be limited by adjustment of the adjusting screws 30. The operator, by grasping the handle 14, moves the carriage to the right of Figs. 1 and 2 and the rollers 6 and 8 55 may engage the screws 34 at the end of this stroke which form stops for the carriage. The carriage is then pushed back by means of the handle 14 to the position shown at Fig. 1, at which time, the handle may be turned over to the position shown in Fig. 5 and in dotted lines 60 in Fig. 4 to release the card 33. At this time, the type may be again inked and a new card inserted in position to be printed. I have not shown the type in Figs. 1, 2, 3, and 4 as any suitable means may be provided for supporting the type 65 which may be arranged in accordance with the design to be printed on the card.

When the carriage is moved longitudinally of the printing bed and the roller is pressed downwardly by pressing downwardly on the handle 70 14, downward pressure is applied to the rollers 6, shown in Fig. 4, and upward pressure is applied to the rollers 7 shown in said figure.

This frees the rollers 5 and 8 from pressure so 75 that there is no grinding action between the flanges of the rollers 5 and 8 and the adjacent

edges of the tracks 3 and bed 1. By thus preventing this grinding action, the carriage will move freely longitudinally of the printing bed.

The pressure of the roller 12 is limited by adjustment of the adjusting screws 30 shown in 5 Figs. 1 and 4. However, as the carriage is moved longitudinally of the printing bed by means of the handle 14 the roller 12 may move upwardly on meeting an obstruction and thus the roller is somewhat yieldable in that it will pass over 10 obstructions and, at the same time, is limited in its downward pressure by said adjusting screws 30.

From the foregoing description it becomes evident that the device is very simple and efficient 15 in operation, will not easily get out of order, is composed of few parts and is of consequent low manufacturing cost and provides a device which accomplishes the objects described.

Having thus fully described my invention, its utility and mode of operation, what I claim and 20 desire to secure by Letters Patent of the United States is—

1. In a card printing machine, a printing bed, a series of type mounted on the printing bed, a carriage movable longitudinally of the printing bed, a transverse member at one end of the printing bed, the transverse member being of the same height as the type on the printing bed, a card clamp member pivotally mounted on the transverse member, spring means urging the card 25 clamp member to clamping position, a member pivotally mounted in the carriage, a pressure roller carried by said member at one side of its pivot, the member being turnable on its pivot in one direction to bring the pressure roller into 30 engagement with the card, a pair of pins carried by the carriage, a spring resisting downward movement of each pin, the member being turnable on its pivot in the opposite direction to depress said pins against the tension of the springs, 35 said pins engaging the clamp member when positioned thereover to turn the clamp member to releasing position.

2. In a card printing machine, a printing bed, a series of type mounted on the printing bed, a carriage movable longitudinally of the printing bed, a card clamp member pivotally mounted at 40 one end of the printing bed and arranged to hold a card in position on the type faces, a member pivotally mounted in the carriage, a pressure 45 roller carried by said member at one side of its pivot, the member being turnable on its pivot to bring the pressure roller into engagement with the card, a handle for turning said member on its pivot and a pair of pins adapted to be engaged 50 by said pivoted member when turned to position to move the pressure roller away from the card, said pins being arranged to engage and release the pivoted card clamp when moved downwardly 55 thereover.

3. In a card printing machine, a printing bed, a transverse member extending across one end of the printing bed, a card clamp member pivotally mounted on said transverse member and having a clamp jaw normally engaging the upper edge of said transverse member, spring means arranged to turn said clamp member on its pivot to move the clamp jaw into engagement with said transverse member, a carriage movable longitudinally of the printing bed, a 70 pair of pins movable vertically in said carriage and a pivoted member in the carriage turnable to position to depress said pins, the pins when positioned over the card clamp member being arranged to engage said member and turn it 75

on its pivot against the tension of the springs to disengage the clamp jaw from the transverse member.

4. In a card printing machine, a printing bed, 5 a carriage movable longitudinally of the printing bed, a card clamp stationarily mounted at one end of the printing bed, a member pivotally mounted in the carriage, a pressure roller carried by said member, the axis of the pressure roller being eccentric to the pivotal axis of the said member, means operated by turning movement of said member in one direction to open the card clamp and allow removal or insertion of the card therein and spring means for closing the card clamp as the member is turned back to normal position.

5. In a card printing machine, a printing bed, a transverse member at one end of the printing bed, a card clamp member pivotally mounted 20 on the transverse member, spring means normally urging the card clamp member to clamping position, a carriage movable longitudinally of the printing bed, a stop at each end of the printing bed for the carriage, the carriage being 25 movable to position over the card clamp member and manually operable means carried by the carriage for disengaging the card clamp member when the carriage is positioned thereover.

6. In a card printing machine, a printing bed, 30 a series of type mounted thereon, a carriage movable longitudinally of the printing bed, a card clamp stationarily mounted at one end of the printing bed and arranged to hold a card in position on the type faces, a member pivotally mounted in the carriage, a pressure roller carried by said member at one side of its axis, means operated by turning movement of said member in one direction to open the card clamp, the

turning movement of the said member in the opposite direction moving the pressure roller into engagement with the card.

7. In a card printing machine, a printing bed, 5 a series of type mounted on the printing bed, a carriage movable longitudinally of the printing bed, a pivoted card clamp mounted at one end of the printing bed, a member pivotally mounted in the carriage, a pressure roller carried by said member at one side of its pivot and 10 means operated by turning of the pivoted member on its pivot to disengage the pivoted card clamp member when the carriage is positioned thereover.

8. In a card printing machine, a printing bed, 15 a carriage movable longitudinally of the printing bed, a card clamp stationarily mounted at one end of the printing bed, a member pivotally mounted in the carriage and means operated by turning of said member to disengage the 20 card clamp when the carriage is positioned thereover.

9. In a card printing machine, a printing bed, a series of type mounted thereon, a carriage movable longitudinally of the printing bed, a 25 card clamp stationarily mounted at one end of the printing bed and arranged to hold a card on the type faces, a member pivotally mounted in the carriage, a pressure roller carried by said member at one side of its axis, means operated 30 by turning movement of said member in one direction to open the card clamp, adjustable means limiting the turning movement of said member in the opposite direction, said turning movement of said member in the opposite direction 35 moving the pressure roller into engagement with the card.

EDD C. OLIVER.
